ACTUATING DEVICE FOR ELECTRIC APPARATUS

Karl Johan Jungholm, Stockholm, Sweden

Application August 24, 1933, Serial No. 686,608

In Sweden August 26, 1932

17 Claims. (Cl. 308—22)

In electric installations in localities which contain inflammables or humid or corroding gases it is for the sake of safety very important that the installation is cut off from the mains 5 of an electric current supply net, when not in use. For this purpose it is necessary to use switches placed outside such localities and in such and many other cases it is desirable to actuate switches or other electric apparatus from 10 a place outside the room in which the electric apparatus is placed. Usually the switch which is outside the installation room is actuated by the operator in the inflammable room by means extending through the partition to the fireproof 15 room, where the switch is located. For actuating the apparatus a shaft is used passing through one or more walls. Many devices were proposed for this purpose but they are generally very expensive, difficult to mount and in many cases 20 not reliable.

The chief purpose of this invention is to create an inexpensive and efficient but also safe device for mounting such shafts passing through one or more walls.

Another purpose of this invention is to create 25 such devices as to be very simple to mount and to be easily and safely mountable by means of few, simple tools at a minimum consumption of time.

Another purpose of this invention is to mount 30 such shafts in plates interconnected by means of a tube enclosing the shaft.

Other purposes of this invention will be evident from the following specification and claims.

Some embodiments of this invention are illustrated in the annexed drawings.

Fig. 1 is a plan view of an electric installation having a switch with an actuating device in accordance with this invention.

Fig. 2 shows a side view, partially in vertical section, of an actuating device in accordance with 40 this invention.

Fig. 2a shows some details of Fig. 2 of a larger scale and with some parts broken away, and 45 with the handle turned 90°.

Fig. 2b shows a section on the line IIb—IIb in Fig. 2a.

Fig. 3 shows a detail of a device intended to prevent mechanical damage on the breaking 50 parts of the switch.

Fig. 4 shows a side view, partially in vertical section, of a modified device in accordance with this invention.

Fig. 4a shows some details of Fig. 4 on a larger 55 scale with some parts broken away.

Fig. 4b is a section on the line IVb—IVb in Fig. 4a.

Fig. 5 shows an end view of part of the rope-actuated lever shown in Fig. 4 and

Fig. 6 shows an end view of the toothed disk 5 connected with said lever.

Fig. 7 shows, partially in vertical section, a detail of another embodiment of the connection between the switch and the actuating shaft.

Fig. 8 is a view of an embodiment, in which 10 the switch is not co-axial with the actuating member.

Fig. 9 shows another embodiment, in which 15 there is a room between the switch and the actuating member.

Fig. 10 illustrates a similar case in which the 20 switch is in addition not co-axial with the actuating member.

Fig. 11 is a cross section on the line XI—XI in Fig. 12 and

Fig. 12 is a detail view, partly in section, to 25 show the connection between an actuating shaft and a shaft of extension to which it is connected.

Fig. 13 is a cross section on the line XIII—XIII in Fig. 12.

Referring now to Fig. 1 of the drawings, A indicates a locality containing inflammables or humid or corroding vapors or the like, while B is an adjacent, dry and fire-proof room. In the locality A is an electric installation, indicated as 30 a whole by C, such as an illuminating installation which may be switched on and disconnected by means of a switch D placed in the room B. To render it possible to actuate this switch from the locality A an actuating member E is connected with the switch D through the wall between the rooms. The invention refers to improvements in such actuating devices passing through walls.

One embodiment of the switch D is shown in 40 Figs. 2 and 2a of the drawings. The switch D is secured to a bracket 2 which is fixed to the wall 3. Through said wall a hole 4 is cut and two discs 5 are arranged at the two ends of said hole. At their inner sides said discs have sockets or tube 45 connections 6 threaded on their inner side and, preferably, integral with the discs 5 (Fig. 2a). A tube 7 threaded on its outer side is screwed into said two tube connections 6 and serves to connect the two discs 5 rigidly. Short pins or 50 screws 8 are inserted through said discs 5 and penetrate into the wall 3 to a short distance. Said pins or screws do not substantially secure the discs to the wall but are merely intended to prevent them from rotating.

25

30

35

40

45

50

55

In the discs 5 two journals 9, 10 are rotatably journaled. To the journal 9 an actuating member in the shape of a handle 11 is secured for instance, by means of a pin 11a and the opposite 5 end of this journal is formed into (is integral with) a connecting socket 12. The journal 10 is connected to the movable part of the switch D at 13 by means of a pin 13a and formed into (is integral with) a connecting socket 14. Between the connecting sockets 12 and 14 an intermediate shaft 15 is inserted. The sockets or 10 journal extensions 12, 14 are engaged by corresponding extensions 15a on the ends of the intermediate shaft 15 to cause the journals and 15 the intermediate shaft to act as an undivided shaft for transmitting rotary motion for actuating the switch. It is to be observed that the journals 9 and 10 are non-slidably journaled in the discs 5 and that the right hand disc 5 together with the parts 9, 11, 12 on one hand and the left hand disc 5 together with the parts 10, 13, 14 on 20 the other hand form assembled aggregates, even before they are mounted on the wall.

In the embodiment shown in Fig. 3 the casing 25 of the switch D is provided with two abutments 16 and to the journal 10 a projection or an arm 17 is secured by a pin 17a to co-operate with the stationary abutments 16 to limit the rotating motion of the actuating shaft and the handle 11 30 so as to prevent over-strains on the breaking parts of the switch.

In Figs. 4, 4a, and 4b the switch D is secured directly to the wall 3 and the shaft of the switch is at right angles to the actuating shaft 9 passing 35 through the wall 3. Said two shafts are interconnected by means of the bevel gear 18, 19. The wheel 18 is keyed on one end of the journal 10 and on the other end of said journal a socket 14b is secured by means of the pin 14a. Thus, 40 the journal 10 is rotatably but non-slidably journaled in the disc 5, forming an aggregate together with the parts 18, 14b, and 14a. The parts 18 and 14b serve as stops, preventing axial motion of said journal 10. The journal 9 is extended 45 to a square rod 9a directly engaging a corresponding recess in the socket 14b, as shown in Figs. 4a and 4b. The actuating device for the switch consists of a rope lever 22 which is disc-shaped and secured to the journal 9 by means of a disc 50 20 secured on the journal 9 by means of a pin 20a. Thus, the journal 9 is prevented from sliding axially by a collar 9b integral therewith and by the disc 20 secured thereto. The right hand disc 5 together with the journal 9 and the disc 20 55 forms a ready-made aggregate even before they are mounted on the wall. Said aggregate is, preferably, assembled in the factory and delivered as a unit. The rope lever and the disc are shown in detail in Figs. 5 and 6. The lever 22 is secured 60 to the disc 20 by means of two screws 23. To render it possible to adjust the rope lever 22 in different angular positions the disc 20 is provided with a number of slots or holes 21 intended to register with the holes 24 cut in the lever 22. By 65 inserting the screws 23 in different holes or slots 21 of the disc 20 the lever 22 may be adjusted to different angular positions. To render it possible to make small adjustments of the angular position of the lever 22 said lever is provided with 70 two pairs of holes 24, so arranged in relation to each other that if the screws 23 are moved from one pair of holes 24 to the other while using suitable holes 21 of the disc 20, the lever 22 is adjusted to an angle, which is only half of the 75 angle (center angle) between two adjacent holes

or slots of the disc 20. In other respects this embodiment is similar to that shown in Figs. 2 and 2a.

In the embodiment shown in Fig. 7 one of the discs 5 forms part of the casing of the switch D. 5

In Figs. 8-10 some embodiments are shown to illustrate cases in which the switch and the actuating device are not co-axial or there is a room between the rooms in which the actuating device and the switch are placed. The invention is, 10 however, not limited to such embodiments but may also be used in combination with other mechanical or electric distance control devices.

In Fig. 8 the actuating member 26 is by means of an actuating shaft in accordance with this invention connected through the wall 3 with a sprocket wheel 27, a rope wheel or the like which via a chain 28, a rope or the like drives a corresponding wheel on the shaft of the switch D. In other respects this embodiment is similar to that 20 shown in Figs. 2 and 2a and corresponding parts carry the same reference characters.

In the embodiment shown in Fig. 9 the actuating member 26 is by means of an actuating shaft in accordance with this invention connected 25 through the wall 3 with an additional shaft or extension 29 passing through the room F between the rooms A and B. The shaft 29 is by means of a second actuating shaft 10 in accordance with this invention connected through the wall 3a with 30 the switch D. In other respects this embodiment is similar to that shown in Figs. 2 and 2a, and corresponding parts carry the same reference characters.

In Fig. 10 an embodiment is shown in which 35 the shafts of the switch and the actuating device are not coaxial and there are rooms between the two rooms in which the switch and the actuating member are placed. The actuating member 26 in the room A is by means of a first actuating 40 shaft connected through the wall 3 with a rope wheel 30 connected via a rope 31 with a rope wheel 32 which is placed upon or connected with a shaft of extension 29 in the room F. In a similar manner the shaft 29 is via a second actuating 45 shaft connected with the switch D in the room B.

A journal and an intermediate shaft, or two journals, or an actuating shaft and a shaft of extension in the devices in accordance with this invention may be coupled together, for instance, 50 as shown in Figs. 11-13.

In Figs. 11-13 the journal 9 is provided with two crossing slots into which the intermediate shaft 15 fits, said shaft having a cross-shaped cross-section. To the journal 9 a coupling disc 55 35 is secured which is bolted to a coupling disc 36 carrying a journal 34a provided with two longitudinal ribs. The shaft of extension 29 is tube-shaped and slotted at one end to engage said ribs. As is evident from Fig. 12, the tube 7 and the tube 60 connections 6 may not be threaded. In such case the tube 7 is only pushed into the tube connections 6.

It is to be observed that the device in accordance with this invention may easily be adapted to 65 different thickness of the walls. For this purpose the intermediate shaft 15 (Figs. 2, 7, and 12) or the journal 9 (Figs. 4 and 12) may to their entire length or to a substantial part of their length have such a cross-section that they—wherever 70 cut off—will with their end or ends fit to the journal or journals and directly engage the latter. Examples of such cross-sections are shown in Figs. 11 and 13. To mount the device it is only necessary to cut off the intermediate shaft or the 75

journal to a length corresponding to the thickness of the wall, whereupon the parts may be directly assembled without further working the same. If a tube like 7 is used to connect the 5 disks 5, said tube is also cut off to a length corresponding to the thickness of the wall. In many cases said tube 7 may advantageously be threaded to its entire length in the factory. In such case it is only necessary to cut off the tube but not to 10 thread the same on the place, on which the device is to be mounted. The only work to be performed on said place is the cutting off and the assembling, while all other work is made in the factory.

15 Analogously, the shaft of extension 29 (Figs. 9, 10, and 12) may have such a cross-section that it—after being cut off to the proper length—will fit to the journals.

The invention is, however, not limited to those 20 embodiments of detachable connections of shafts and journals shown and described.

It is to be observed that the discs 5 may be secured to the wall 3 (Figs. 2 and 4) exclusively by means of the screws 8; the tube 7 and the 25 sockets 6 being then superfluous.

It is to be observed that the discs 5 may be provided with holes, abutments or the like for a tool, such as a wrench, to facilitate the turning of said discs, when screwing them on the tube 7.

30 What I claim is:—

1. In a device for actuating an electric apparatus through a house wall, having a hole therethrough, in combination, two discs secured at the two ends of said hole through said wall, two 35 separate journals rotatably journaled coaxially, independently of each other, and permanently unslidably in the axial direction, one in each of said discs to form two permanently assembled units adapted to be inserted one from each end 40 of said hole, means for coupling said two rotatable journals together within said walls, said coupling means being detachable by pulling said units apart without loosening any locking means, an operative mechanical connection between one of said journals and the electric apparatus to be actuated, and an actuating member connected with the other of said journals.

2. In a device for actuating an electric apparatus through a house wall having a hole therethrough, in combination, two discs secured at the two ends of the hole through said wall, a journal operatively connected with said apparatus, a handle, and a second journal rigidly connected with said handle, said two separate journals being journaled rotatably but axially unslidably independently of each other and coaxially in each of said discs, respectively, to form two permanently assembled units adapted to be inserted one from each end of said hole, means including engaging flanges and recesses for detachably interconnecting said two journals mechanically in the interior of the hole through said wall.

3. In a device for actuating an apparatus through a wall, having a hole therethrough, in combination, an actuating shaft on said apparatus, a rotary journal mechanically and operatively connected with said actuating shaft, a second rotary journal, an intermediate shaft, two 50 discs secured one at each end of the hole through said wall, said two journals being coaxially and rotatably journaled each in one of said discs and adapted to engage said intermediate shaft by means of a recess and projection connection at their ends facing each other, an actuating mem-

ber on said second journal, and stops on each of said journals to prevent said journals from sliding axially in said discs, each of said discs together with the corresponding journal forming a permanently assembled unit.

4. In a device for controlling an apparatus mechanically through a wall having a hole therethrough, in combination, an actuating shaft on said apparatus, a rotary journal mechanically and operatively connected with said shaft, a second rotary journal, two discs placed at both ends of the hole through said wall, a threaded tube screwed into said discs to press them against said wall, said two rotary journals being detachably interconnected and coaxial and rotatably but axially substantially unmovably journaled each in one of said discs and partially enclosed by said tube, steps on said rotary journals adapted to prevent them from sliding axially in said discs, even when said discs are dismounted, and an actuating member on said second journal.

5. In a device for controlling an electric switch through a wall having a hole therethrough, in combination, a casing on said switch, a switch shaft rotatably journaled in said casing, a rotary journal mechanically connected with said switch shaft, a second rotary journal, a disc forming a part of said casing, a second disc, said two discs being placed one at each end of the hole through said wall and forming coaxial bearings for said two rotary journals which are coupled together by means of a recess and flange connection, an actuating member on said second journal, and stops on said rotary journals adapted to prevent them from sliding axially in said discs, even when said discs are dismounted from said wall.

6. In a device for controlling an apparatus through a wall having a hole therethrough, in combination, a casing enclosing said apparatus, an actuating shaft rotatably mounted in said casing, a bevel wheel on said actuating shaft, a rotary journal, a second bevel wheel secured to said journal and meshing with said first bevel wheel, a disc forming a part of said casing, a second rotary journal, a second disc, said two discs being placed one at each end of the hole through said wall and forming coaxial bearings for said two rotary journals which are coupled together by means of a recess-and-flange-connection, an actuating member on said second journal, stops on said journals to prevent them from sliding axially in said discs, even when said discs are dismounted together with said journals, each of said discs together with the corresponding journal therein forming a finished, preassembled unit.

7. In a control device for actuating an apparatus through a wall having a hole therethrough, in combination, two discs secured one at each end of the hole through said wall, two coaxial journals rotatably but unslidably in their axial direction journaled one in each of said discs, one of said rotary journals being mechanically and operatively connected with an actuating shaft for said apparatus, an actuating member mechanically and operatively connected with the other of said journals, and a slot-and-flange connection between those ends of said journals which face each other.

8. In a control device for actuating an apparatus through a wall having a hole therethrough, in combination, two discs secured one at each end of the hole through said wall, two coaxial journals rotatably journaled one in each of said discs, said rotary journals being prevented from slid-

- ing axially in said discs, even before said discs with said journals are mounted in said wall, an actuating shaft for said apparatus mechanically and operatively connected with one 5 of said rotary journals, an actuating member mechanically and operatively connected with the other of said journals, and a slot-and-flange connection between those ends of said journals which face each other, said connection 10 comprising also an intermediate shaft.
9. In a control device for actuating an apparatus through a wall having a hole therethrough, in combination, two discs secured one at each end of the hole through said wall, two coaxial journals 15 rotatably journalled one in each of said discs, said rotary journals being prevented from sliding axially in said discs, even before said discs with said journals are mounted in said wall, an actuating shaft for said apparatus mechanically and 20 operatively connected with one of said rotary journals, an actuating member mechanically and operatively connected with the other of said journals, and an intermediate shaft, said journals and said intermediate shaft having such cross-sections 25 that they will detachably engage each other, when cut off to correspond to the thickness of said wall.
10. In a control device, for actuating an apparatus through a wall having a hole therethrough, in combination, two discs secured one at each end 30 of the hole through said wall, two coaxial journals rotatably journalled one in each of said discs, said rotary journals being prevented from sliding axially in said discs, even before said discs with said journals are mounted in said wall, an actuating 35 shaft for said apparatus mechanically and operatively connected with one of said rotary journals, an actuating member mechanically and operatively connected with the other of said journals, and an intermediate shaft, said journals and 40 said intermediate shaft having such cross-sections that they will fit into each other with a detachable slot-and-flange connection without being further worked, when cut off to correspond to the thickness of said wall.
- 45 11. In a control device for actuating an apparatus through a wall having a hole therethrough, in combination, two discs placed one at each end of the hole through said wall, a tube threaded substantially to its entire length and screwed into 50 said discs to press them against said wall, two coaxial journals permanently rotatably journalled one in each of said discs and at least partially enclosed by said tube but immovable in their axial direction, even when said discs are removed from 55 said wall, one of said journals being mechanically and operatively connected with said apparatus while the other of said journals is mechanically and operatively connected with an actuating member for said apparatus, and an intermediate 60 shaft, said journals and said intermediate shaft having such cross-sections that they will fit into each other with a detachable slot-and-flange connection without being further worked, when cut off to correspond to the thickness of said wall.
- 65 12. In a mechanism for actuating an electric device through a wall having a hole therethrough, in combination at each end of the hole through said wall, a disc, a journal rotatably and unslidably journalled in said disc and forming finished 70 permanently preassembled units, a mechanical coupling on one end of each of said journals to connect said journals with and detachable only by pulling one of said discs away from said wall, and a connection on the other end of one of said 75 journals to connect the same with the electric

device on one side of said wall, and an actuating member on the other journal on the opposite side of said wall from said electric device.

13. In a mechanism for controlling an electric device through a stationary wall of a building 5 having a hole therethrough, in combination, two discs at the ends of said hole, two journals each rotatably and unslidably journalled in one of said discs to form finished assemblies therewith, an actuating shaft for said electric device mechanically 10 connected with one of said rotary journals, an actuating member mechanically connected with the other of said journals, and an intermediate rod, said journals and said intermediate rod having such cross sections that they will form 15 within said wall a detachable mechanical coupling without further shaping the said cross-sectional shape of said rod extending for a substantial distance along said rod whereby the rod may be cut to suit the thickness of the wall without changing 20 the sectional shape of its end.

14. In a device for controlling an electric apparatus mechanically through a house wall having a hole therethrough, in combination, an actuating shaft passing through said hole through said wall, 25 an operative mechanical connection between one end of said shaft and said apparatus, an actuating member mechanically and operatively connected with the other end of said shaft, two separate discs one at each end of said hole respectively, 30 bearings in said discs for said shaft, and a separate tube between said discs extending through said hole connecting and centering said discs in a coaxial relation.

15. In a device for controlling an electric apparatus mechanically through a house wall having a hole therethrough, in combination, a divided shaft passing through the hole through said wall and at one end mechanically and operatively connected with said apparatus to be controlled, an 40 actuating member mechanically and operatively connected with the other end of said shaft, two separate discs, one at each end of said hole, bearings for said shaft in said discs, said discs having threaded holes therein, and a threaded tube between said discs, said tube enclosing said shaft in said hole and engaging the threaded holes in said discs and forming a rigid aggregate together with said discs, said discs having their bearings 45 firmly centered coaxially by said tube.

16. In a device for controlling an electric apparatus mechanically through a house wall having a hole therethrough, in combination, a shaft passing through the hole through said wall and at one end mechanically and operatively connected with 55 said apparatus to be controlled, an actuating member mechanically and operatively connected with the other end of said shaft, two separate discs one at each end of said hole, bearings for said shaft in each of said discs, a threaded tube between said discs, said discs being provided with threaded sockets engaged by the threaded ends of said tube, whereby rigid aggregate is formed with said discs and said bearings are centered coaxially, said discs being firmly pressed against 60 both sides of said wall by said tube.

17. In a device for controlling an electric apparatus mechanically through a house wall having a hole therethrough, in combination, a shaft passing through the hole through said wall, said shaft 70 being at one end mechanically and operatively connected with said apparatus to be controlled, an actuating member mechanically and operatively connected with the other end of said shaft, two separate discs one at each end of said hole 75

respectively, bearings in said discs for said shaft, a tube threaded to its entire length and extending between said discs, said discs being provided with threaded sockets engaged by said threaded tube, 5 whereby a rigid aggregate with said discs is formed and said bearings are centered in a coaxial

relation, said tube enclosing said shaft, said discs being firmly pressed against both sides of said wall by said tube, regardless of whether or not the sides of the wall are exactly parallel.

KARL JOHAN JUNGHOLM. 5
